UNITED STATES PATENT OFFICE.

ROGER B. EAMES, OF SOUTH FRAMINGHAM, MASSACHUSETTS.

DESIGN FOR A BICYCLE HANDLE-BAR.

SPECIFICATION forming part of Design No. 29,527, dated October 18, 1898.

Application filed September 17, 1898. Serial No. 691,248. Term of patent 14 years.

To all whom it may concern:

Be it known that I, ROGER B. EAMES, a citizen of the United States, residing at South Framingham, in the county of Middlesex and State of Massachusetts, have invented and produced a new and original Design for a Bicycle Handle-Bar, of which the following is a specification, reference being had to the accompanying drawings, forming a part thereof, in which—

Figure 1 is a perspective view of a handle-bar embodying my design, and Fig. 2 is a top plan view of the same.

The design comprises an L-shaped member consisting of the stem A, the base B, the extension C of the stem beyond the angle of junction of the stem and base, and the arm D, ex-

tending rearwardly and laterally from the L-shaped member at an angle to the stem of the L-shaped member. At the outer ends of the stem A and arm D appear enlargements, which, however, are minor features of my design.

The leading feature of my design consists of the L-shaped member and the arm extending rearwardly and laterally at an angle to the stem of the L-shaped member.

I claim—

The design for a bicycle handle-bar, herein shown and described.

ROGER B. EAMES.
